UNITED STATES PATENT OFFICE

FRANK LEBRECHT, OF NEW YORK, N. Y.

DESIGN FOR A TABLE COVER OR SIMILAR ARTICLE

Application filed May 21, 1930. Serial No. 35,712. Term of patent 3½ years.

To all whom it may concern:

Be it known that I, FRANK LEBRECHT, a citizen of the United States, residing at New York, in the county of New York and State of New York, have invented a new, original, and ornamental Design for a Table Cover or Similar Article, of which the following is a specification, reference being had to the accompanying drawing, forming part thereof.

Fig. 1 is a face view of a table cover, or similar article, showing my new design.

Fig. 2 is an enlarged fragmentary view of a corner of the same taken within the area bounded by the dot and dash lines.

Fig. 3 is an enlarged detailed view of one-quarter of Fig. 1.

The dominant feature of the design consists in the provision of parallel spaced lines and other parallel spaced lines at right angles to the first group of lines forming boxes, and parallel lines within said boxes and parallel to one set of said spaced lines forming a background which fills each of the boxes.

I claim:

The ornamental design for a table cover or similar article, as shown and described.

In testimony whereof I have affixed my signature.

FRANK LEBRECHT.
